METAL DETECTING PICK-UP COIL

Thomas H. Doss, P.O. Box 10563, Houston, Tex. 77018

Filed June 12, 1970, Ser. No. 23,454

Term of patent 14 years

Int. Cl. D10—04

U.S. Cl. D52—1

FIG. 1

FIG. 2

FIG. 3

FIG. 1 is a perspective view showing the metal detecting pick-up coil;

FIG. 2 is a lower face view illustrating the relationship of the concentric circles of the metal detecting pick-up coil; and,

FIG. 3 is a side view of the structure shown in FIG. 2.

The broken line showing of a fragment of a handle is included in FIG. 1 for illustrative purposes only.

What is claimed is:

The ornamental design for a metal detecting pick-up coil, as shown and described.
